**VISIBLE INDICATOR CONTROL SYSTEM FOR
SELECTIVE TAPE TRACK**

Carl Thumim, Lombard, Ill., assignor to Miehle-Goss-Dexter, Incorporated, Chicago, Ill., a corporation of Delaware

Filed Aug. 20, 1962, Ser. No. 217,899
1 Claim. (Cl. 340—226)

This invention relates to paper cutting machines and more particularly to paper cutting machines of the type that have back gauges movable in accordance with a selected program of recorded magnetic tape signals.

In a previously filed application Serial No. 840,281, for Magnetic Tape Control Systems, filed September 16, 1959, by Carl Thumim, assigned to the present assignee, there is disclosed a programming system for moving a back gauge automatically in predetermined steps in accordance with the spacing of signals on magnetic tape. The signals are recorded in a plurality of recording channels extending longitudinally of the tape, and any channel may be selected for effecting a series of cuts in a paper pile having any predetermined distance between cuts. In a particular machine now in commercial use, there are eight such channels recordable on magnetic tape and the system includes magnetic pick-up head means movable transversely across the tape to any selected channel position, or automatically, to a sequence of channel positions. When the magnetic head stops at a particular channel, the signals in such channel are utilized for controlling movement of the back gauge for determining the length of cuts to be taken. The general organization of such a control mechanism is shown in detail in the previously mentioned patent application, including the mechanism for selecting a sequence of channels to which the head is to move in accordance with selection and throwing of a plurality of respective switches accessibly to the machine operator.

A difficulty with the system as disclosed in the prior application, is the fact that there is no manifestation whereby an operator is apprised of the actual operation of the pick-up head subsequent to his command signals. Thus, when the head is moving intermediate the channels, the operator is not made aware of the actual motion of the head, nor as to whether or not it has reached a particular channel or has become operative in such channel. The present invention is for the purpose of overcoming such drawback and has for its primary object the provision of a series of signal lamps associated with respective channels which apprise the operator that the pick-up head has reached a particular channel, and that read-out is taking place on such channel subsequently.

Briefly, the invention contemplates a control panel at the front of the machine, visible to the operator and comprising a series of manual switches which the operator manipulates to select a sequence of channels to be put into programming use. Each switch is associated with a particular channel and two lamps, each of a different color, are associated with each switch. Thus, when a particular switch is selected, a white lamp lights up to indicate such selection. Likewise, where a series of switches in a row of switches are selected, the white lamp associated with each switch lights up upon any such switch being thrown. Subsequently, movement of the pick-up head transversely across the tape engages respective channel micro-switches; and upon such engagement an amber lamp associated with the channel switch on the control panel lights up while at the same time the white lamp associated with that switch is extinguished. The specific amber lamp remains lit while that channel is in use and the operator is thus apprised of the channel then being in control of the back gauge and also of all subsequent channels remaining to take over control in

2

sequence since the white lamps for such channels remain lit.

A detailed description of the invention now follows, in conjunction with the appended drawing, in which:

5 FIGURE 1 shows the control panel layout at the front of the machine;

FIGURE 2 shows diagrammatically a portion of the control circuitry for the channel selector system.

FIGURE 1 will be seen to comprise a panel 10 carrying a series of eight white lamps 13 associated with respective switches S₁—S₈, such switches being multi-pole switches having *a* and *b* sections. Similarly, a row of eight amber lamps 20 are associated with respective switches. At the left side of the control panel will be seen a switch 24 for determining control of the back gauge in accordance with manual or automatic tape control as desired, and also various switches 26, 28 and 30, designated as forward, reverse and advance, for effecting corresponding functions of the back gauge in a conventional manner.

At the right hand end of the panel are button switches 32, 34, 36 to control the functioning of the tape recorder in conjunction with the knife of the machine, the arrangement including various signal colored lamps, 40, 42 and 44. When it is desired to make recording continuously, the button 32 is pressed which causes continuous flashing of red lamp 40 to indicate that a template is moving under the knife and that markings thereon are being picked up for recording. When a cut is made and button 34 is pressed, the lamp 42 shows up as a white light. At the same time, the lamp 40 will signify by a flashing red light that the recording is being made. When the button 36 is pressed, lamp 40 remains energized continuously and the recording is then automatic. Button 44 is used for tape erasure, yellow lamp 44 being energized at that time.

Referring now to FIGURE 2, one proposed system for energizing the indicator lamps of the central portion of the control panel is shown. Thus, the tape 50 having eight recording channels, C₁—C₈, is moved in the direction of the arrow A. A magnetic head 55 will be understood to be actuated transversely of the tape by a motor 69, reversibly, in the direction of the double-headed arrow B. The motor 60 is started and stopped under control of motor control system 65, in accordance with the disclosure in my previously filed patent application, whereby the head stops sequentially at pre-selected channels in accordance with selection of switches S₁—S₈. Switch S₁ is shown in position to condition the motor control system 65, via the *b* section of the switch, for moving the pickup head to the first channel C₁.

55 Since S₁—S₈ are multipole switches, upon being actuated they effect current flow from source V, via the *a* sections of the switches, through normally closed relay contacts of a respective relay 70 (one shown) to energize the white lamp 13 associated with that switch. However, when any relay is energized under conditions described below, the contacts are opened and the white lamp associated therewith is extinguished.

Each of the channels has associated therewith a micro-switch 80, which can be engaged by a cam 85 carried by the magnetic head 55. Accordingly, when the head stops at any particular channel, the corresponding micro-switch is maintained continually closed. Each micro-switch controls electric current from source V to steadily energize the associated amber lamp 20.

60 The operator is thus apprised of the fact that the magnetic head has reached a selected channel. Since each amber lamp 20 is shunted by a normally closed relay 70, such relay is energized when the lamp is energized and the associated white lamp 13 is then extinguished.

65 Accordingly, when any selection of switches S₁—S₈ is made, the associated white lamps are energized. How-

ever, as the magnetic head stops at selected channels, the respective white lamp is extinguished and the respective amber lamp is energized. After the program of a particular channel has been traversed, and the magnetic head moves to the next channel, the associated amber lamp for that channel is extinguished, inasmuch as the cam 85 then disengages from the respective micro-switch 80.

It will be apparent, from the above description, that an operator at the front of the machine will always be aware of the operation of the tape recording and read-out system, particularly as to the channel then in effect and subsequent channels to go into sequential effect.

Having thus described my invention, I am aware that various changes may be made without departing from the spirit thereof and, therefore, do not seek to be limited to the precise illustrations herein given, except as set forth in the appended claim.

The embodiments of the invention in which an exclusive privilege or property is claimed are defined as follows:

In a visual indicating system for an automatically programmed back gauge, a record member having a plurality of spaced programming signal channels, a plurality of respective switches for said channels, a plurality of respective indicator lights of one color for said channels, means whereby operation of a selected switch effects energization of a respective indicator light, a sensing head and means for effecting movement of said head relative to said record member for positioning said head adjacent a selected channel responsive to operation of a

selected switch, a plurality of respective indicator lights of another color for said channels, a respective circuit control means adjacent each channel and individually operative by said sensing head, circuitry means controlled by operation of any circuit control means for de-energizing the indicator light of said one color associated with a selected channel and energizing an indicator light of said other color when said sensing head is positioned at said selected channel.
